CUFF LINK

Alfred E. Dixon, Providence, R. I., assignor to
Ostby and Barton Company, a corporation of
Rhode Island

Application February 25, 1938, Serial No. 192,441

3 Claims. (Cl. 24—102)

This invention relates to a cuff link; and has for one of its objects the provision of a construction which will be extremely simple and one which will accordingly be inexpensive to manufacture.

Another object of the invention is the provision of a cuff link with a movable head which may be made by cutting the parts from sheet stock with a minimum number of parts, namely, two for assembly whereby a movement of one part relative to the other may be had.

Another object of the invention is the provision of a structure from which various ornamental head configurations may be had.

With these and other objects in view, the invention consists of certain novel features of construction, as will be more fully described, and particularly pointed out in the appended claims.

In the accompanying drawing:

Fig. 1 is a perspective view of the cuff link in working position;

Fig. 2 is a view similar to Fig. 1 but showing one of the heads as swung about its pivot to a position for insertion into the button holes of the cuff;

Fig. 3 is a perspective view of one of the pieces of stock bent into position prior to assembly;

Fig. 4 is a perspective view of the other piece of stock forming one of the head members;

Fig. 5 is a perspective view of the structure of Fig. 4 but looking at the opposite or inner surface thereof;

Fig. 6 is a plan view of the stock as cut from a sheet prior to the bending illustrated in Fig. 2.

Cuff links of a character having movable parts so that one part may be moved relative to the other for easy insertion into the cuff followed by a subsequent movement to prevent extraction of the link from the cuff are desirable; and in order to make such a link of utmost simplicity I have provided two parts and so shaped the stock forming these parts that they may be pivoted together in the form having spaced heads with a shank connecting the heads, all of which may be accomplished at minimum cost; and the following is a more detailed description of the present embodiment of this invention, illustrating the preferred means by which these advantageous results may be accomplished:

With reference to the drawing, I have illustrated in Fig. 6 a sheet of stock blanked out in the particular shape shown and slotted as at 10 so that the extending portions or members 11 and 12 may be bent up along the slit 10 and folded along the line 13 into generally parallel

relationship, as shown in Fig. 3, to provide a shank portion of the link. The end portions of the members 11 and 12 are reduced as at 14 and turned outwardly so as to provide pivot trunnions for the other head member of the link.

The other head member is designated 15 and is cut from sheet stock slotted as at 16 with portions 17 folded along the fold lines 18 to provide ears 19 which have openings 20 therein. The ears 19 are partially folded and then the head 10 positioned so that when the fold is completed the trunnions 14 will extend into the openings 20 in the ears that a pivotal relation of the parts may be had, as shown in Figs. 1 and 2. This relationship is such that the head 15 may be 15 positioned as shown in Fig. 2, for insertion of the head through the button hole of a cuff, after which the head may be swung to the position shown in Fig. 1 to prevent extraction of the link from the button holes of the cuff.

It will be readily apparent from the above that the particular shape of the head 15 or of the head 21 may be varied that different designs may be provided, it being usually desirable that some symmetrical configuration which will conform 25 well with the notches 22 or 23 as provided by bending of the stock to form the pivoting portions will be desirable.

The foregoing description is directed solely towards the construction illustrated, but I desire 30 it to be understood that I reserve the privilege of resorting to all the mechanical changes to which the device is susceptible, the invention being defined and limited only by the terms of the appended claims.

I claim:

1. A cuff link comprising two pieces of sheet stock, one piece providing a head with folded members extending therefrom at right angles thereto and providing a shank, the other member having ears sheared therefrom inwardly of the edges thereof and folded in spaced relation and provided with openings receiving the ends of said shank members to pivotally relate the parts.

2. A cuff link comprising two pieces of sheet stock, one piece providing a head with folded members extending in spaced parallel relation therefrom at right angles thereto and a substantial distance inwardly of the edges thereof with 50 the ends outturned and providing a shank, the other member having ears folded therefrom and provided with openings receiving the outturned ends of said shank members to pivotally relate the parts.

3. A cuff link comprising two pieces of sheet stock, one piece consisting of a head having shank portions folded from the stock thereof a substantial distance inwardly of the edges of the head and extending in spaced relation from each other and with the ends outturned, the other member

having ears sheared therefrom inwardly of the edges thereof and folded in spaced relation and provided with openings receiving the ends of said shank members to pivotally relate the parts.
